Chrysler Corporation, Highland Park, Mich., a corporation of Delaware

Application April 28, 1955, Serial No. 35,725

Term of patent 14 years

(Cl. D14—3)

FIG. 1.

FIG. 2.

Fig. 1 is a side elevational view of an automobile showing my new design;

Fig. 2 is an enlarged fragmentary side elevation of a portion of Fig. 1 with the side opposite being similar to the one illustrated; and

Fig. 3 is an enlarged top plan view of the portion shown in Fig. 2.

The characteristic features of my design reside in the portions shown by means of full lines in the drawings.

I claim:

The ornamental design for an automobile, substantially as shown and described.
